BURNER

James A. Whittington, Evanston, Ill.

Application April 8, 1940, Serial No. 328,413

1 Claim. (Cl. 158—99)

The present invention relates in general to burners and is particularly concerned with an improved gas burner of the type generally known as a "Bunsen" burner.

Heretofore, burners of this type were of such design and operated in such manner that the burners had to be constructed of different sizes and dimensions for each type of gas with which the burner was to be utilized. That is, if a burner, for example, were to be utilized for the burning of a gas having a comparatively high B. t. u. content such as iso-butane, the burner in order to operate efficiently had to have its parts relatively so proportioned as to size as to provide the proper mixture for this particular gas, whereas for a gas such as the so-called "mixed" gas having a relatively low B. t. u. content a different size burner with parts of different sizes and proportions was necessary. Due to the difference in sizes in the burners required for the different gases with which the burners might be utilized, it was heretofore necessary for the burner manufacturer to build or the burner supplier to provide a plurality of burners of different sizes, thus materially increasing the cost of manufacture and the cost of stocking the burners.

The present invention broadly contemplates an improved burner of such construction and design that the size of the burner may be standardized irrespective of the particular gas utilized in the burner. To this end, in my improved burner, the mixing chambers and air inlet openings are standardized as to their relative proportions and may be used without change for all the gases commonly available for burners of this type. The size of the gas inlet orifice is the only part which is varied in my burner to adapt it for use with a particular one of the available gases.

This construction is of tremendous advantage from the standpoint of the cost of manufacture and in the maintenance of burner stocks. The burner may be initially fabricated, without a gas orifice, as a simple standardized stock item or unit available for use with any of the usual gases. All that is then necessary to commission the burner for use with a particular gas is to provide the stock unit with an orifice of proper predetermined size depending upon the particular gas with which the burner is to be utilized. Since this orifice is in the form of a round passage, it will require but one simple operation to commission the burner for use with any one of the gases, and this commissioning operation may be simply accomplished by means of a proper size drill.

Moreover, a burner embodying the features of

construction of my invention having a standard size and overall dimension for utilization with the different gases is further advantageous in that it may be most efficiently utilized in boilers, refrigerators, and other commercial and industrial applications. For example, such a burner enables the use of a standard mounting to provide the most efficient spacing between the burner tip and the surface of the body being heated, thus making it unnecessary to vary this distance for different installation conditions wherein different gases may respectively be utilized.

It is a further object of the herein described invention to provide an improved burner construction which will operate with extremely high efficiency; which will be free from back-fire, carbonization and other undesirable operating characteristics; and in which the various parts of the burner are relatively so proportioned in such

20 novel manner as to maintain a practically constant air-gas ratio during variation of the gas pressure over a wide range, a feature which was heretofore thought could only be attained in a burner with a Venturi type of mixer.

25 It is a further object of the present invention to provide an improved burner construction adjacent the efflux end of the gas admitting orifice for the collection of dirt, lint and other foreign matter to keep it from occluding the orifice, particularly under operating conditions in which the gas may be admitted at a comparatively low pressure.

30 A further object of the invention is to provide an improved construction at the combustion end 35 of the burner tip for facilitating the successive lighting off of a plurality of adjacently disposed burners from each other after one of the burners has been lighted.

40 A still further object of the invention is to provide an improved method of making or constructing a gas burner.

45 Still another object is to provide an improved method of burning various gases in a single burner of the herein described type.

Other objects and features of the invention will more fully appear from the following detailed description taken in connection with the accompanying drawing, which illustrates a single embodiment thereof, and in which:

Figure 1 is a vertical longitudinal sectional view through a burner constructed in accordance with the features of the herein described invention;

Figure 2 is a plan view of the same;

Figure 3 is a fragmentary view in elevation

looking toward the air inlet opening of the burner;

Figure 4 is a transverse sectional view taken through the burner at the position of the air inlet opening, taken substantially on line IV—IV of Figure 1;

Figure 5 is a fragmentary sectional view showing an alternative construction at the efflux end of the burner gas orifice; and

Figure 6 is a fragmentary sectional view showing an alternative construction at the combustion end of the burner.

As shown on the drawing:

As illustrative of the burner of my present invention, I have selected a construction as shown in detail on the drawing, this construction embodying the features of operation and utilization as will hereinafter be disclosed in detail.

In general, the burner of the present invention embodies an elongate tubular body as generally indicated at 10 which may be constructed of any suitable material such as brass, bronze and the like. The lowermost end of the burner body is tapered and threaded as shown at 11 to enable connection of this end to a suitable gas supply for the burner. The opposite end is in the form of a contracted tubular portion 12 which is preferably integrally formed with the body of the burner. Intermediate the ends of the burner, the body is preferably formed with a polygonal outer surface for receiving a suitable wrench or tool, whereby the burner may be rotated during its connection to a suitable base or other supporting structure through which gas may be supplied to the burner.

An elongate tubular sleeve 13 is disposed with its lowermost end margin surrounding the tubular extension 12, the lowermost end of the sleeve being in abutting relation with a peripherally extending abutment shoulder 14 at the lowermost end of the extension 12 where the extension joins the burner body. The sleeve 13, it will be noted,

chamber 17 at its uppermost end communicates with a second stage expanding or mixing chamber 18 which is in axial alignment with the first stage chamber.

5 It will be noted that the juncture of the first and second stage chambers is connected by an abrupt shoulder or surface 19 which acts to set up eddy currents or a certain amount of turbulence as the combustible mixture passes from the first stage chamber to the second stage chamber, thus materially enhancing the mixing of gas and air before it reaches the opening 15 at the uppermost end of the sleeve 13.

The lowermost end of the burner body is provided with a central bore or passage 20 for gas which leads to a gas orifice or nozzle 21 of tubular form and predetermined cross-sectional area, as will later be described in detail.

The gas efflux end of the nozzle is centrally disposed at the lowermost end of the chamber 17.

In order to supply air or other supporter of combustion to the gas issuing from the orifice 21, the body of the burner is provided with a laterally cut slot 22 which extends into the lower end 25 of the chamber 17 and is adjacent to or proximate to the discharge end of the gas orifice. The bottom surface or floor 23 of this slot is preferably even or level with the discharge end of the orifice as shown.

30 While the foregoing describes in a general manner, the construction of my improved burner, it has been found that in order to successfully operate the burner and efficiently burn the combustible mixture of gas and air and prevent backfiring of the burner, the air inlet, mixing chambers and the gas orifice must be proportioned as to length, size, etc. in a very definite relationship.

35 In determining the relationship and proportions between the various parts of my improved burner, the combustion constants of the various gases have been taken into consideration and are listed in the following Table A:

extends an appreciable distance beyond the outermost end of the extension 12 to define an outlet 15 at the uppermost end of the sleeve. The uppermost end of the sleeve 13 is preferably provided with a chamfer 16 or similar bevel to aid in the inflow of air to the burner flame for supporting combustion thereof at the opening 15.

In the construction shown, the body 10 of the burner and the extension 12 cooperate to define an elongate tubular passage or bore 17 which constitutes a first stage chamber for the mixing of air and gas admitted to the burner. The

65 It is generally well known that the weight of air required to liberate a B. t. u. from a gas is, for all practical purposes, substantially constant for the different gases, and, that as between gases having different B. t. u. contents the amount of air required for combustion will be proportional to the B. t. u. contents of the respective gases.

70 By reference to Table A, column 5, it will be noted that the weight of gas for a given B. t. u. content is substantially constant. With a knowledge of the foregoing relationships, it can be shown that the weight of air required for the

combustion of quantities of the various gases sufficient to liberate a desired or given heat value is substantially constant. This constancy is shown in Table A, column 7.

The commercial gases available for use with burners of the herein described type are usually composed of the combustible gases listed in Table A, either singly or in various proportions, together with inert gases such as carbon dioxide and nitrogen, and a small amount of oxygen. Since the weight of air required to liberate a given heat value from the various gases is substantially constant, as previously pointed out, it therefore follows that the weight of air required for mixtures of these various gases to liberate the given heat value, will remain substantially the same as for that of only one of the gases.

It will therefore be apparent that with these substantially constant factors in the various gases, if the air inlet opening to the burner is made of such size as to be capable of admitting the required amount of air for combustion, the size of this opening may be made constant and of fixed value irrespective of the gas which is being utilized, provided the gas orifice and gas pressures at the manifold are properly determined. Since the rate of admission or injection of the air into the gas is known to be a function of the gas momentum as it issues from the gas orifice, it is therefore possible to provide an orifice of proper size to admit the required amount of gas to liberate whatever B. t. u. per hour heating effect may be desired, for example, 3200 B. t. u. per hour, and that by utilizing the proper gas entering pressure, the momentum of the gas stream may be maintained substantially constant.

When the proper size orifice and gas pressure are determined, no other change in the burner design is necessary for satisfactory operation with a particular gas. It will therefore be apparent that with a burner of proper design, the mixing chambers and the air inlet opening may be constant factors in the burner, and the only variable in the burner construction is the size of the gas orifice.

By way of a specific example, a burner designed to liberate 3200 B. t. u. per hour when a gas is burned therein, will have the dimensions as indicated in the following Table B:

TABLE B

Burner parts	Dimension
<i>a</i>	
<i>b</i>	.221
<i>c</i>	.31250
<i>d</i>	1.500
<i>e</i>	1.375
<i>f</i>	.081
	.0625

In general, it will be noted that with the above dimensions the cross-sectional areas of the first stage chamber and the second stage chamber will be in the ratio of substantially one to two, that the first and second stage chambers are of substantially the same length and that the air inlet opening is of a fixed dimensional height.

It has been found through experiment that the inlet air opening should have an area at least as great as the area of cross-section of the first stage chamber. With the height of air inlet slot as specified above, the length of the slot to give a proper size opening would extend through an angle of substantially 268° , or, in other words, through an angle greater than one-half of the

interior circumference of the first stage mixing chamber. With such a construction, as shown in Figure 4, it will be noted that the inner part of the slot will therefore extend a substantial distance past the efflux end of the gas orifice.

Since the dimensions of the burner as given in Table B are of constant determination irrespective of the gas with which the burner is to be used, the burner will have constant overall dimensions. The burner may therefore be constructed as a standard unit or stock item, without an orifice therein, and may subsequently be commissioned at any time desired for use with a particular gas simply by drilling the proper size orifice, as shown in Table A, column 9. Column 10 shows the proper gas pressure to be used in each case with the burner for the particular gas for which the burner has been commissioned, regulating means being provided usually at the place of installation so that the gas pressure may be regulated to the desired value.

For example, if it is desired to burn 3200 B. t. u. per hour of 800 B. t. u. "mixed" gas, the burner would have an orifice with a cross-sectional area of .00138 sq. inch, such as would be produced by a standard No. 58 drill, and the proper gas pressure to utilize at the manifold would be 3 inches water column.

As initially constructed, the bore 20 is closed by a partition relative to the first stage mixing chamber. Thus, when it is desired to commission the burner for a particular gas, all that is necessary is to drill an opening of proper size through this partition to form a gas orifice interconnecting the bore 20 with the first mixing chamber.

Since the amount of air inspirated into the gas is dependent upon the momentum of the gas leaving the orifice, the air-gas ratio remains substantially constant for the various gases with changes in their pressure.

In the following Table C, I have shown the air-gas ratio for a burner of the present invention when utilized with an 800 B. t. u. "mixed" gas:

TABLE C

Air-gas ratios

[800 B. t. u. mixed gas]

	Pressure, inches water	Gas rate	Per cent gas	Air-gas ratio	Per cent air
50	0.5	1.64	26.0	2.85	74.0
	1.0	2.23	24.0	3.17	76.0
	2.0	3.33	23.5	3.26	76.5
	3.0	4.08	24.5	3.08	75.5
	4.0	4.79	24.0	3.17	76.0
	5.0	5.48	23.5	3.26	76.5

It will be noted from the above table that the gas pressure may be varied over a wide range without materially affecting the air-gas ratio. A very efficient burner therefore results in which complete combustion will take place, and backfiring, blowing from the ports, and other undesirable operating characteristics will be eliminated.

Referring to Figure 5 of the drawing, I have disclosed an alternative construction at the efflux end of the burner gas orifice. In this construction instead of making the floor 23 of the air admitting slot even or level with the discharge end of the orifice as shown in Figure 1, the portion of the floor lying within and adjacently surrounding the orifice is provided with an annular groove or recess 24. This groove or recess forms a downwardly extending extension of the first

stage chamber and does not interfere with the efficient operation of the burner, the outlet end of the orifice being retained as before at the floor level of the air inlet slot. This alternative construction is particularly advantageous, when the burner is utilized with low gas entrance pressures, as it prevents the accumulation of dirt, lint and other foreign matter at the orifice, which might otherwise occlude the orifice and affect its proper functioning. This construction is especially desirable, when the burner is to be utilized as a pilot light.

In Figure 6, of the drawing, I have shown an alternative construction in which the uppermost end of the sleeve 13 instead of being provided with an outside chamfer 16 is provided with an inside chamfer as shown at 25. This arrangement gives a slight flare to the burning flame and is especially advantageous in that it facilitates the successive lighting off of a plurality of adjacently mounted burners one from the other, after one of the burners has been lighted.

While in the disclosed burner construction, I have shown the first and second stage mixing chambers as being formed of separate parts, it will be readily appreciated that the extension 12 and sleeve 13 may, if desired, be integrally formed of one piece.

It is thought that the improved method of constructing a burner of this type, as well as the improved method of burning a gas in such burner will be readily apparent from the foregoing description of my improved burner.

From the foregoing description, it will be apparent that the present invention provides an improved burner of the Bunsen type which may be initially provided as a standard unit with fixed

dimensions; which may be readily commissioned for use with any one of a plurality of different gases merely by providing a proper sized orifice as determined by the particular gas for which the burner is to be utilized; which will operate with high efficiency, is free from backfire, carbonization, and other undesirable operating characteristics; a burner in which the various parts thereof are relatively so proportioned as to maintain a practically constant air-gas ratio during variations in gas pressure over a wide range; which is so arranged as to facilitate the successive lighting off of a plurality of adjacently mounted burners, when one of the burners has been lighted; which utilizes a novel construction in which occluding of the burner gas orifice by foreign matter is effectively prevented, especially at low gas pressures; which embodies an improved method of making a gas burner; and which utilizes an improved method for burning of the gas.

It is of course to be understood that although I have described in detail a preferred embodiment of my invention, the invention is not to be thus limited, but only insofar as defined by the scope and spirit of the appended claim.

I claim as my invention:

A burner comprising a body member having an elongate passage open at one end and a gas orifice at the other end thereof, and an air admitting slot in said body at the junction of said orifice and passage extending partially through the body from one side thereof with its inner end terminating between the longitudinal axis 35 of the body and the opposite side thereof.

JAMES A. WHITTINGTON.
